OTOSCOPE

Arthur J. Pulos, Fayetteville, N.Y., assignor to Welch Allyn, Inc., Skaneateles Falls, N.Y.

Filed Sept. 2, 1970, Ser. No. 24,793

Term of patent 14 years

Int. Cl. D24—02; D16—08

U.S. Cl. D57—1

FIG. 1

FIG. 2

FIG. 3

FIG. 4

FIG. 5

FIG. 6

FIG. 1 is a perspective view of an otoscope embodying my new design, with the battery containing handle for the otoscope shown in phantom lines;

FIG. 2 is a top plan view thereof;

FIG. 3 is a right side elevation thereof;

FIG. 4 is a left side elevation thereof;

FIG. 5 is a rear elevation thereof; and

FIG. 6 is a front elevation thereof.

The broken lines which represent a conventional battery handle on which the otoscope is mounted during use are shown for illustrative purposes only.

I claim:

The ornamental design for an otoscope, as shown and described.
